CLAIM

The ornamental design for the welding gun, as shown and described.

DESCRIPTION

FIG. 1 is a top, front and right-side perspective view of a welding gun showing my new design;
FIG. 2 is a right side elevational view;
FIG. 3 is a top plan view;
FIG. 4 is a left side elevational view;
FIG. 5 is a front elevational view;
FIG. 6 is a rear elevational view;
FIG. 7 is a bottom plan view;
FIG. 8 is a top, front and right-side perspective view of a second embodiment of my new design of FIGS. 1-7;
FIG. 9 is a front elevational view of FIG. 7;
FIG. 10 is a rear elevational view of FIG. 7;
FIG. 11 is a right side elevational view of FIG. 7;
FIG. 12 is a top plan view of FIG. 7;
FIG. 13 is a left side elevational view of FIG. 7; and,
FIG. 14 is a bottom plan view of FIG. 7.

FIG. 1

FIG. 2

FIG. 3

FIG. 8

FIG. 9

FIG. 10
